UNITED STATES PATENT OFFICE.

JONATHAN T. BROWN, OF MARBLEHEAD, MASSACHUSETTS, ASSIGNOR, BY MESNE ASSIGNMENTS, TO O. A. MILLER TREEING MACHINE COMPANY, OF BROCKTON, MASSACHUSETTS, A CORPORATION OF MAINE.

DISPLAY-FORM.

SPECIFICATION forming part of Letters Patent No. 777,272, dated December 13, 1904.

Application filed July 11, 1902. Serial No. 115,146. (No model.)

To all whom it may concern:

Be it known that I, JONATHAN T. BROWN, of Marblehead, in the county of Essex and State of Massachusetts, have invented certain new and useful Improvements in Display-Forms, of which the following is a specification.

- This invention relates to forms, followers, and lasts, herein referred to as "shoe-forms" or "forms" which are employed for determining, preserving, or restoring the shapes of boots and shoes, and particularly to that class of shoe-forms which are made in two parts connected together preferably at a single pivotal point in such manner that the 5 form may be shortened for insertion into or withdrawn from a shoe and may be lengthened, so as to fill out the shoe after having been placed therein. The shoe-form herein shown is especially adapted for use with low-cut or Oxford shoes in which the upper portion of the form is exposed above the top of the shoe; but of course the invention is not limited in any way to shoe-forms adapted for this use.
- 10 One of the features of my invention consists in a divided shoe-form having a single part adapted to fill completely the upper portion of a low-cut shoe, so that when the form is in such a shoe it will present to view only
- 15 unbroken surfaces like a solid shoe-form.

Another feature of the invention consists in constructing the heel part of a shoe-form with a member or extension adapted to support a portion of the instep of the shoe, there- 20 by reducing the tendency of the shoe to collapse the form.

Other features of the invention, including certain details of construction and combinations of parts, will be herein described, and 25 pointed out in the claims.

Figure 1 is a side elevation, partly in section, of a shoe-form embodying my invention in one of the best forms now known to me, a shoe being shown upon the form. Fig. 2 is 30 a similar view of the shoe-form collapsed or

flexed, as when it is being inserted in a shoe or withdrawn from a shoe.

The shoe-form comprises a heel part 1 and a fore part 3, connected preferably at a single pivotal point by a hinge 20. The line of 35 division between the fore part and heel part extends from the instep on the upper side to the bottom of the form, so that the portion of the form occupying the opening at the top of the shoe between the counter and the instep is all comprised in the heel part 1, and the top face of the shoe-form has a continuous or unbroken surface 13. The heel part comprises a forwardly-projecting member or sole-piece 2 and a forwardly-projecting member 40 or instep-piece 9, the upper member or extension 9 having on its outer end a surface which is adapted to support the upper part of the instep portion of the shoe. The fore part has a member 4 for supporting the lower portion of the instep of the shoe. Preferably the portion 4 of the fore part extends upwardly and backwardly to or near the instep-supporting portion 9 of the heel part. The shoe-form is cut away between the fore part 45 and the heel part, as at 5, for the purpose of permitting the relative movement of the parts of the hinge 20. The face 11 of the fore-part member 4 and the faces 10 and 12 of the heel-part member 9 are formed to slide freely with 50 relation to each other as the parts are moved on the hinge 20. The adjacent faces 7 and 8 below the hinge serve as stops to limit the movement of the parts in the direction for extending the form, and preferably, also, the 55 faces 11 and 12 contact when the shoe-form is in its extended condition. It will be observed that when the heel part of the form is turned up for collapsing the form the height of the form measured through the lower portion of the instep is decreased, thus making it easier to put the form into a shoe and to take it out. The location of the pivotal connection between the fore part and the heel part may be varied; but said connection is 60

preferably so located in advance of the instep-supporting surface, or it may be under said surface, that the tension of the upper over the said instep-supporting surface has no tendency to collapse the shoe-form. It is to be noted that the heel part with its forwardly-extending member or sole-piece 2, together with the fore part or toe member, constitute the bottom face of the form, and when the shoe-form is extended the entire bottom of the shoe is engaged and held in proper position by these parts.

In using the shoe-form the instep portion of the shoe is distended and supported by the movable heel part of the form, and when the shoe-form is used with low-cut shoes it presents a better appearance than other forms, because the part which is exposed to view above or through the top of a shoe is a solid portion without any lines of division, thus giving the appearance of a one-piece shoe-form.

Having thus explained the nature of my invention and described a way of constructing and using the same, though without attempting to set forth all of the forms in which it may be made or all the modes of its use, what I claim, and desire to secure by Letters Patent, is—

30 1. A foot-form comprising a heel member formed with a sole-piece extending toward the ball portion of the form, a toe member having its bottom surface arranged as an extension of that of said sole-piece and formed with an integral instep-block separated from said sole-piece by a recess, an extension on the heel member closing the rear end of said recess and adapted to play close to but past the end of said block, and a hinge connecting the end 40 of the sole-piece to said toe member, whereby the instep measure of the form may be lessened by a movement of the sole-piece toward the instep-block.

2. A display form or follower comprising fore and heel parts hinged together, the heel part having a recess with an instep-support projecting forward over said recess, and having an upper portion forming a continuous or unbroken surface to the instep, and the fore 50 part having a rearward extension movable from a position in line with the instep portion of the heel part to a position along the bottom of said recess.

3. In a shoe-form, a fore part and a heel 55 part pivotally connected, the heel part being formed with a recess in its end adjacent the fore part and with an instep-supporting member, and a rearwardly-extending member on said fore part adapted to be moved from a 60 position in line with the instep-supporting member of the heel part into a position along the bottom of the recess.

4. A shoe-form comprising a fore part and

a heel part hinged together, the heel part being formed with a recess in its end adjacent the fore part and having an instep-supporting member, the upper portion of said heel part forming a continuous or unbroken top surface of the shoe-form, and a rearwardly-extending member on the fore part movable from a position in line with the instep-supporting member of the heel part to a position along the bottom of said recess.

5. In a shoe-form, a fore part and a heel part pivotally connected, said heel part having a forwardly-extending member adapted to support the instep of the shoe, and one of said parts being cut away to form a recess for permitting the form to be collapsed by a movement of the other part into the recess. 75

6. In a shoe-form, a fore part and a heel part, the heel part being provided with an instep-supporting surface, and having a pivotal connection to the fore part, said pivotal connection being located in advance of the instep-supporting surface of the heel part, whereby collapse of the form by pressure of the shoe on said instep-supporting surface will be prevented. 85

7. In a shoe-form, a fore part and a heel part connected at a single pivotal point, said heel part having a forwardly-extending member adapted to support the instep of the shoe. 90

8. In a shoe-form, a fore part and a heel part connected at a single pivotal point, the heel part having an instep-supporting member projecting forwardly therefrom, and the upper portion of said shoe-form presenting a continuous or unbroken top surface. 95

9. In a shoe-form, a fore part and a heel part connected at a single pivotal point and constructed to present only continuous or unbroken surfaces to view when the form is in place in a shoe. 100

10. In a divided shoe-form, a fore part and a heel part connected at a single pivotal point, the line of division between said two parts intersecting the bottom and the instep of the form, but not the top face thereof. 105

11. A shoe-form comprising a fore part and a heel part, the heel part being provided with an instep-supporting surface and connected at a single pivotal point, said pivotal point being positioned with relation to the said instep-supporting surface to prevent collapse of the shoe-form by pressure of the shoe on said instep-supporting surface. 110

12. In a shoe-form, a fore part and a heel part, the heel part being provided with a portion adapted to support the instep of a shoe 120 and having a forwardly-extending member, a pivotal connection between said member and the fore part, the said fore part having a rearwardly and upwardly extending member separated from the forwardly-extending member 125 of the heel part by a recess, the heel part

forming the rear wall of said recess and being adapted for movement toward and from said fore-part member to increase and diminish the height of the form measured through 5 the said fore-part and heel-part members.

13. A shoe-form presenting a continuous or unbroken top surface and comprising a fore part and a heel part pivotally connected, said parts being shaped for permitting relative

movement to collapse the form and for preventing increase of instep - measure of the form when it is collapsed.

In testimony whereof I have affixed my signature in presence of two witnesses.
